ATTORNEY.

UNITED STATES PATENT OFFICE.

ALBERT J. DOTY, OF PHILADELPHIA, PENNSYLVANIA, ASSIGNOR TO THE GOODWIN GAS-STOVE AND METER COMPANY, OF SAME PLACE.

HEATING GAS-STOVE.

SPECIFICATION forming part of Letters Patent No. 331,950, dated December 8, 1885.

Application filed April 9, 1884. Serial No. 127,149. (No model.)

To all whom it may concern:

Be it known that I, ALBERT J. DOTY, residing in Philadelphia, in the county of Philadelphia, State of Pennsylvania, have invented a new and Improved Heating Gas-Burner, of which the following is a specification, reference being had to the annexed drawings, forming a part thereof.

In gas-stoves as ordinarily made the heat generated by the combustion of the gas is distributed by multiplying burners, or by making the burners of great size, thereby necessarily increasing the quantity of gas required to produce a given amount of heat. Where single burners are employed, the heat is more or less concentrated at one or more points, and not uniformly distributed. In gas cooking-stoves this feature is particularly objectionable.

The object of my invention is to provide a burner for gas-stoves which will distribute the heat uniformly throughout the entire area of the stove, and will at the same time heat the combustible mixture of air and gas before ignition, so that combustion will be immediate and complete.

My invention consists in an apertured concavo-convex plate having on the convex side thereof a gas and air tube communicating with the central aperture of the plate, and arranged in connection with the concavo-convex plate to form a Bunsen burner, and in the combination therewith of a deflecting-plate placed opposite and near the opening in the concavo-convex plate on the concave side.

In use my improved burner is placed in a gas-stove with the concavo-convex plate arranged horizontally, or nearly so, and with the concave side thereof downward.

Figure 1 is a side elevation, partly in section, of a gas-stove having my improvement applied. Fig. 2 is an inverted plan view of my improved burner, partly in section.

Similar letters of reference indicate like parts in the different figures of the drawings.

A concavo-convex plate, A, preferably of cast-iron, and of a size and shape corresponding with the stove to which it is applied, and of which it forms a part, is secured in the stove-body with its concave side downward, as shown in Fig. 1. A circular aperture, B,

formed centrally in the plate A, is traversed by a cross-bar, a, for receiving a screw or rivet for supporting a circular concave deflecting-plate, C, below and near the said aperture. 55 The deflecting plate C is larger in diameter than the aperture B, and is designed to spread the gas and flame issuing from the aperture B over the under surface of the plate A.

Upon the convex side of the plate A is fitted 60 a hollow casting, D, over a rib, e, formed on the back of the plate A. The casting D is tubulated, and the tubular end d projects through the wall of the gas-stove to receive an apertured cap, e, which is secured thereon by 65 clamping-screws f, passing through the sides of the cap and bearing against the tube. In the central aperture of the cap e is screwed a gas-injecting nozzle, E, concentric with the tube d, and there are air-openings g in the 70 cap e on each side of the gas-injector nozzle E.

Gas enters the burner through the nozzle E with sufficient velocity to draw in air through the openings g. The gas and air mix in the cavity of the casting D, and the mixture is 75 propelled forward through the aperture B, where it is ignited. The flame and gas issuing from the aperture B strike the deflecting-plate C, and the flame spreads over the concave surface of the plate A and heats the said 80 plate uniformly throughout. The gas and air in their passage over the plate A to the aperture B are heated, so that the combustion of the mixture is intense and complete, and the full heating-power of the gas is utilized. 85

I do not limit or confine my invention to the exact form and proportions herein shown and described, as it may be modified to conform to the various requirements of use. Although I prefer the concavo convex form for the plate 90 A, it may be made plain, and instead of employing cast-iron for the said plate I may use fire-clay or other refractory material.

My improved burners may be applied to larger uses by increasing their size or employing a number of burners, or by increasing the number of openings in the plate A for the combustible mixture.

I am aware that heating-burners have been constructed in which the gas has been distributed before ignition by passing it through series of holes or slots; but such construction

is objectionable on account of the liability of such holes and slots to become clogged. I make no claim to such construction. In my invention the gas is not distributed until after it is 5 ignited.

Having thus described my invention, what I claim as new, and desire to secure by Letters Patent, is—

The combination, with a concavo-convex

plate, A, having a central aperture, B, of the ~~the~~ 10 tubulated casting D, connected to the top of the plate, and the deflecting-plate C beneath the opening, as herein specified.

ALBERT J. DOTY.
